J. W. FISCHER,

RAZOR.

APPLICATION FILED JAN. 7, 1916.

1,264,045.

Patented Apr. 23, 1918.

UNITED STATES PATENT OFFICE.

JOSEPH W. FISCHER, OF BROOKLYN, NEW YORK.

RAZOR.

1,264,045.

Specification of Letters Patent. Patented Apr. 23, 1918.

Application filed January 7, 1916. Serial No. 70,779.

To all whom it may concern:

Be it known that I, JOSEPH W. FISCHER, a subject of the Emperor of Austria, and a resident of the city of New York, borough 5 of Brooklyn, in the county of Kings and State of New York, have invented a new and Improved Razor, of which the following is a full, clear, and exact description:

The object of the invention is to provide 10 a new and improved razor of the usual type and having a safety guard arranged to permit using the razor without the safety guard or handling the razor with the guard applied and with either hand for conveniently 15 and safely shaving both sides of the face without danger of cutting the skin.

In order to produce the desired result, use 20 is made of a razor blade having an integral tang, and two guards fulcrumed on opposite sides of the tang and adapted to overlie the sides of the blade, one of the guards being adapted to form a handle for the 25 razor while the other guard overlies the corresponding side of the razor blade. Use 30 is also made of means for fastening the free ends of the guards together to provide a casing for the razor blade or a handle for the razor whenever it is desired to shave without the guard.

35 A practical embodiment of the invention is represented in the accompanying drawings forming a part of this specification, in which similar characters of reference indicate corresponding parts in all the views.

38 Figure 1 is a perspective view of the razor with one guard in position on the blade and the other guard forming the handle of the razor;

40 Fig. 2 is a similar view of the same with both guards fastened together to form a handle for the razor and to allow shaving without the guard;

45 Fig. 3 is a side elevation of the razor with both guards in closed position to form a casing for the razor;

Fig. 4 is an enlarged cross section of the 50 razor on the line 4—4 of Fig. 1;

Fig. 5 is an enlarged sectional plan view of the same on the line 5—5 of Fig. 3;

55 Fig. 6 is an enlarged cross section of the same on the line 6—6 of Fig. 3;

Fig. 7 is an enlarged side elevation of the pivotal connection between the guards and the tang of the razor blade; and

55 Fig. 8 is a cross section of the same on the line 8—8 of Fig. 7.

The ordinary razor blade 10 is provided with an integral tang 11 on opposite sides of which are pivoted the shanks 12 and 13 of two razor guards 14 and 15 adapted to 60 overlie the razor blade 10 on opposite sides thereof. The razor guards 14 and 15 are provided with suitably spaced prongs 16 and 17 curved to extend close to the cutting edge of the blade 10 to prevent the cutting 65 edge from cutting into the skin whenever the razor is used with either of the guards 14 or 15 in active position relative to the razor blade 10. The prongs 16 and 17 are arranged alternately, as plainly indicated in 70 Figs. 3 and 5, to permit the prongs to pass each other at the time both guards 14 and 15 are in position on opposite sides of the blade 10 (see Fig. 6), or the guards form a handle as shown in Fig. 2.

The guards are provided with pivoted hooks 20 and 21 adapted to hook over the back of the blade, the hooks when not in use lying in the recesses 22 and 23 of the 75 guards.

The free ends of the guards 14 and 15 are adapted to be fastened together to form a casing for holding the razor blade 10 between the guards (see Fig. 3) or for forming the razor guards into a unitary structure 80 such as a handle to permit using the razor without a guard, as illustrated in Fig. 2. For the purposes mentioned use is made of a hook 25 pivoted at 26 to the free end of the guard 15 and adapted to engage a lug 27 90 formed on the free end of the guard 14, as plainly indicated in Fig. 5. The hook 25 when not in use is sprung back into a recess 28 formed in the guard 15, as indicated in dotted lines in Fig. 5. The forward ends 95 of the guards 14 and 15 are provided at their opposite faces with integral lugs 30 and 31 adapted to abut against each other to hold the free ends of the guards 14 and 15 properly spaced apart and without danger of binding on the blade 10 (see Fig. 5).

The pivotal connection between the guards 14, 15 and the tang 11 is made adjustable to hold the prongs 16, 17 in proper relation to the cutting edge of the blade 10 whenever 105 the latter is reduced in width by occasional grinding. For this purpose the following arrangement is made, special reference being had to Figs. 7 and 8: A pivot 40 is held transversely in the tang 11 and extends 110 through plates 41 and 42 held on opposite sides of the tang 11 and extending into ver-

tical grooves 43 and 44 formed in the inner faces of the shanks 12 and 13 of the guards 14 and 15. The plates 41 and 42 are provided with bolts 45, 46 extending through slots 47 and 48 formed in the shanks 12 and 13, and the said bolts 45 and 46 pass through clamping plates 49, 50 held on the pivot 40 and extending in grooves 51 and 52 formed in the outer faces of the shanks 12 and 13. 10 Nuts 53 and 54 screw on the outer threaded ends of the bolts 45 and 46 and against the plates 49 and 50 to clamp the shanks 12 and 13 between the plates 41, 49 and 42, 50. When the width of the blade 10 is reduced 15 by grinding then the nuts 53, 54 are loosened to allow of adjusting the shanks 12 and 13 between the corresponding pairs of plates 41, 49 and 42, 50 to adjust the prongs 16, 17 in proper relation relatively to the cutting 20 edge of the blade 10. When this has been done the nuts 53 and 54 are screwed up to clamp again the shanks 12 and 13 in position between the plates 41, 49 and 42, 50.

From the foregoing it will be seen that by 25 the arrangement described either of the guards 14 or 15 can be moved into guarding position relatively to the blade 10 to permit of using the razor for shaving with the right or left hand either side of the face.

30 It will also be noticed that when the guards 14 and 15 overlie the blade 10 at both sides thereof then the razor blade 10 is securely incased between the said guards to allow of conveniently storing or shipping 35 the razor without danger of injuring the cutting edge of the blade 10.

It will further be noticed that when the guards 14 and 15 are connected with each other in the manner above described and as

shown in Fig. 2, then the two guards form 40 a handle for the razor to allow of using the latter without a guard.

Having thus described my invention, I claim as new and desire to secure by Letters Patent:

1. A razor, comprising a razor blade provided with a tang, and guards pivoted on opposite sides of the tang and adapted to overlie the sides of the blade, one of the guards being adapted to form a handle for the razor 50 while the other guard overlies the corresponding side of the razor blade, each guard having a stop for engagement by the cutting edge of the blade to limit the movement of the corresponding guard relative to the razor blade, and each guard having a recess and a pivoted hook adapted to hook over the back of the razor blade, said hook when not in use lying in said recess.

2. In a razor, a blade having a tang, a pivot in the said tang, a pair of spaced plates on each side of the tang and through which the pivot passes, the inner plates being provided with threaded lugs passing through the outer plates and provided with nuts, and guards mounted upon the pivot between the said plates, the guards being provided with recesses to receive the said plates, and with slots to receive the said threaded lugs.

In testimony whereof I have signed my name to this specification in the presence of two subscribing witnesses.

JOSEPH W. FISCHER.

Witnesses:

THEO. G. HOSTER,
GEORGE H. EMLIE.
